(57) **CLAIM**

The ornamental design for a sterilization apparatus, as shown and described.

DESCRIPTION

FIG. 1 is a first side view of a sterilization apparatus showing the new design;

FIG. 2 is a second side view thereof;

FIG. 3 is a front-side view thereof;

FIG. 4 is a rear-side view thereof;

FIG. 5 is a top-side view thereof;

FIG. 6 is a bottom-side view thereof;

FIG. 7 is an isometric view thereof, from a generally front, side and top viewing position;

FIG. 8 is a perspective view thereof, from a generally front, side and top viewing position; and,

FIG. 9 is another perspective view thereof, from a generally rear, side and top viewing position.

The broken lines in the drawing views illustrate portions of the sterilization apparatus that form no part of the claimed design; the broken lines form no part of the claimed design.
